RECORD MAKING MACHINE

Oscar J. Sundstrand, Hartford, Conn., assignor to
 Underwood Elliott Fisher Company, New York,
 N. Y., a corporation of Delaware

Application June 16, 1938, Serial No. 214,008

13 Claims. (Cl. 197—2)

This invention relates to adding machines, calculating machines, typewriters and machines of this general class equipped with mechanism for driving certain parts of the machine from an electric motor and more particularly to a drive control mechanism for machines of this class.

In the usual machines of this class having an electric motor drive, the motor is arranged normally to run continuously during the operations of the machine. In order to prevent waste of power such machines have been provided with mechanism of various constructions for cutting off the current from the motor when the machine is idle for a predetermined interval. The present invention relates to a mechanism for this purpose which will be hereinafter referred to as an automatic motor cut-out.

Certain objects of the invention are to improve and simplify the construction and mode of operation of automatic motor cut-out mechanisms and to provide machines of the general class above indicated with a novel and improved mechanism for breaking the motor circuit when the machine is idle for a predetermined interval.

Another object of the invention is to provide machines of the above class having printing mechanism and a carriage, which is moved to position relatively the printing mechanism and the work sheet or sheets, with an automatic motor cut-out mechanism controlled by the movement of the carriage.

Another object of the invention is to provide for typewriting machines, a novel and improved mechanism for cutting off the motor circuit when the machine is out of operation for a predetermined interval.

Another object of the invention is to provide, for typewriting and other machines having a type carriage which is moved to locate relatively the typing mechanism and the work sheet or sheets, an automatic motor cut-out mechanism for cutting off the current from the motor when the carriage is idle for a predetermined interval.

With the above objects in view the invention consists in a mechanism embodying the novel and improved features, constructions and combinations of parts hereinafter described and particularly pointed out in the claims, the advantages of which will be readily understood and appreciated by those skilled in the art.

The invention will be clearly understood from the accompanying drawings illustrating the invention in its preferred form and the following detailed description of the constructions therein shown.

In the drawings:

Fig. 1 is a perspective view looking from the front of the mechanism and illustrating the motor cut-out mechanism applied to a typewriting machine of the Elliott Fisher type,

Fig. 2 is a perspective view looking from the rear and illustrating particularly the carriage return mechanism of the machine,

Fig. 3 is a detail plan view illustrating particularly the mechanism for advancing the carriage,

Fig. 4 is a view in side elevation illustrating the mechanism shown in Fig. 1,

Fig. 5 is a detail view in front elevation illustrating certain of the parts shown in Fig. 4 in the same positions as in said figure,

Fig. 6 is a view in side elevation illustrating a portion of the mechanism shown in Fig. 4 with certain of the parts in different positions,

Fig. 7 is a view similar to Fig. 5 illustrating the parts in the same positions as in Fig. 6,

Fig. 8 is a view similar to Fig. 6, showing certain of the parts in still different positions,

Fig. 9 is a view in rear elevation illustrating the automatic motor cut-out mechanism with the parts in substantially the positions shown in Fig. 4,

Fig. 10 is a view similar to Fig. 9 illustrating the parts in substantially the positions shown in Fig. 6, and

Fig. 11 is a perspective view illustrating certain of the parts shown in Fig. 1 taken from the opposite side of the mechanism.

The invention is illustrated in this application as applied to a typewriting machine of the Elliott Fisher type having substantially the same general construction, arrangement and mode of operation of the parts as the machine shown in the patent to Foothrap No. 1,904,127, dated April 18, 1933. Only so much of the machine shown in said patent as relates particularly to the present invention is illustrated and described in this application.

The machine is provided with the usual platen frame. Mounted to travel over the platen longitudinally of the platen frame is a line space frame, only a portion of which is illustrated in this application. Upon the line space frame is mounted to travel transversely of the platen, upon suitable guide rails, a type or key carriage upon which is assembled the usual printing mechanism operated by keys. The platen frame, the line space frame and the type or key carriage, except for certain driving connections herein described between the motor and the carriage return shaft, preferably have substantially the

same construction, arrangement and mode of operation as the corresponding mechanisms illustrated and described in said Foothorap Patent No. 1,904,127.

5 In the drawings the type carriage of the machine is indicated at 2. The carriage 2 is mounted for movement laterally of the machine upon forward and rear rails carried by the line space frame of which the rear rail is indicated at 4.

10 The carriage is provided with the usual series of wheels or rolls for engaging said rails, one of which, indicated at 6, engages the rear rail 4.

The carriage is moved along the rails of the line space frame in a right hand direction during 15 the operation of the machine by means of a flexible band 8 attached at one end by means of a bracket 10 to the carriage which band is wound about the usual spring drum 11 mounted upon a bracket 12 attached to the rail 4. The drum is 20 acted upon by a spiral spring (not shown) which tends constantly to turn the same in a counter-clockwise direction (Fig. 3) and to move the type carriage along the rails in a right hand direction. Upon the depression of any of the type keys, the 25 tabulating key or the release key, the carriage will be moved to the right by the action of the spring drum 11, on the tape or band 8.

The machine is provided with the usual carriage return rack 14 secured to the flanged rear 30 end of the apron 16 projecting from the deck 18 of the key carriage. Meshing with this rack is a carriage return pinion 20 secured to a sleeve 22 rotatably mounted on and slideable longitudinally of the carriage return shaft 24. To the 35 rear end of this sleeve is attached a clutch member 26 arranged to engage a cooperating clutch member 27 fixed to the carriage return shaft.

The mechanism for driving the carriage return shaft comprises a spur gear 28 secured to the 40 rear end of said shaft, a spur gear 29 attached to the rear end of a counter-shaft 30 and meshing with the gear 28, a bevel gear 32 secured to the forward end of the counter-shaft 30, and a bevel gear 34 fixed to the shaft 36 extending substantially parallel with the carriage guide rails, said gear meshing with the gear 32. To the shaft 36 adjacent one end thereof is attached a spiral gear 38 meshing with a spiral gear 40 fixed to a short shaft 42 arranged substantially parallel with the 45 shaft 36. Upon the shaft 42 is secured a pulley 44 connecting said pulley with a pulley 46 fixed to the shaft 48 of an electric motor 50 suitably mounted on the line space frame and arranged to run continuously during the operation of the 50 machine. Through the gear connections described the carriage return shaft 24 is driven in a clockwise direction as indicated by the arrow (Fig. 2) to impart return movements to the type carriage. The shafts 24, 30, 36 and 42 are mounted 55 in suitable bearings carried by the line space frame.

When the carriage is to be returned to fully or partly returned position, assuming that the motor is running, the clutch member 26 is engaged with the clutch member 27 and the pinion 20 is driven in a clockwise direction (Fig. 2) thereby moving the carriage in a right hand direction in said figure. The usual mechanism shown in said Foothorap patent is provided for 60 moving the sleeve 22 longitudinally of the carriage return shaft 24 to engage the clutch member 26 with and to disengage said clutch member from the clutch member 27.

65 As shown in the drawings, an arm 52 fixed to 70 a rock shaft 54 mounted on the line space frame 75

is provided at its upper end with a roll engaging in a groove in the sleeve 22. To the shaft 54 is secured a second arm 56 and the sleeve 22 is normally held in position on the shaft 24, with the clutch member 26 disengaged from the clutch member 27, by means of a latch 58 pivoted loosely on the carriage return control rock shaft 60 mounted in bearings on the line space frame and extending in a direction substantially parallel with the direction of movement of the carriage, said latch being arranged to engage a contact piece on said arm. The arm 56 and the latch 58 are acted upon by a coiled spring 62 attached at one end to a pin 64 mounted on said arm and at the other to a pin 65 mounted on the latch. 10 The latch and arm are controlled to control the engagement of the members of the clutch by means of a tapered arm or fish tail 66 fixed to the shaft 60 and entered between the pins 64 and 65, these pins being held by the spring 62 in engagement with the opposite edges of said arm as shown in Fig. 2.

The position of the rock shaft 60 is controlled by means comprising a bail 67 carried by arms 68 secured to said rock shaft, the bail extending 25 substantially parallel with the rock shaft. This bail is rocked forwardly to engage the members of the clutch and is rocked rearwardly to disengage the same. Mechanism for rocking the bail forwardly by means of a key 68^a is shown in this 30 application. Mechanism (not shown herein) is preferably provided for rocking the bail forwardly automatically when the carriage reaches the end of a line of writing and for rocking the bail rearwardly automatically when the carriage reaches the limit of its return movement. The automatic mechanism and the key mechanism for rocking the bail preferably have substantially the same construction, arrangement and mode of operation as the corresponding mechanisms shown and described in applicant's pending application Serial No. 149,571 filed June 22, 1937. 40

The circuit of the motor is illustrated diagrammatically by dot and dash lines. The current is received from any suitable source indicated at 69 and the conductors of the circuit are indicated at 70. In the circuit of the motor 50 is a switch 71 which is arranged to be manually operated. Means is provided for automatically opening the motor circuit after the lapse of a brief period, say, one or two minutes, following the last movement of the carriage, so that in the event that the operator fails to open the switch 71, the motor will be automatically stopped. To this end a contact 72 in the motor circuit is arranged to be withdrawn from a cooperating contact 73 in said circuit to break the motor circuit. The contact 72 is mounted at one end of a strip 74 of flexible, resilient conducting material bolted to an insulating block 75 mounted on a plate 76 secured to the clutch housing 77. The contact 73 is mounted on a similar strip 78 of metallic conducting material bolted to the insulating block 75. Two of the conductors 70 of the motor circuit are connected respectively to the strips 74 and 78. The housing 77 is provided with brackets 79 secured to a plate 80 and this plate is attached by means of screws to the rear rail 4 of the line space frame. 55

The mechanism for withdrawing the contact 70 72 from the contact 73 comprises a lever 82 pivoted at 84 on the plate 76 and having a stud 86 of insulating material projecting laterally from a downwardly extending arm on the lever so as to engage the under side of the strip 74 upon 75

which the contact 72 is mounted. The downward movement of the lever 82 is limited by means of a stop screw 88 secured in the plate 76. Pivoted at 90 to the lever 82 is a link 92. This link is moved upwardly to disengage the contact 72 from the contact 73 by mechanism connected with a shaft driven continuously during the running of the motor.

This mechanism comprises a gear wheel 94 rotatably mounted by means of a stud 96 on the plate 76 and meshing with a pinion 100 also rotatably mounted on said plate by means of a stud 104, the gear wheel being spaced from the plate by means of a spacing device 101. Fixed to the pinion 100 is a ratchet wheel 106 which is arranged to be turned by means of a dog 108 pivoted on one arm of an oscillating lever 110. A spring 112 tends to move the dog 108 in a direction to maintain the same in engagement with the ratchet wheel. The dog is moved longitudinally to actuate the ratchet wheel by the oscillations of the lever 110 which is pivoted at 114 on the plate 76. The other arm of the lever is arranged to engage an eccentric 116 fixed to a gear wheel 118 rotatably mounted on the plate 76 by means of a stud 120, which gear wheel meshes with a pinion 122 secured to the shaft 36, the lever being held in contact with the eccentric by means of a coiled spring 124. The shaft 36 is rotated continuously during the operation of the motor. By the mechanism described, the lever 110 is continuously oscillated during the operation of the motor and the ratchet wheel 106 is turned in a counter-clockwise direction (Fig. 4) by the action of the dog 108 thereby turning the gear wheel 94 in a clockwise direction. Because of the relative sizes of the gears 40 and 38, the pinion 122 and the gear 118 and the pinion 100 and the gear 94, and because of the nature of the driving connection between the gear 118 and the ratchet wheel 106 the gear 94 is driven at very slow speed with relation to the speed of the shaft 48 and the driving motor.

The link 92, under certain conditions, is held by a coiled spring 126 in engagement with a stop pin 128, in which position its lower end lies to the right (Fig. 4) of the path of a pin 130 herein-after described. The link is arranged to be engaged at its right hand edge by a pin 129, projecting from the face of the gear wheel 94, at a certain point in the rotation of the gear wheel. By the engagement of said pin with the edge of the link, the link is swung to the left (Fig. 4) into the path of the pin 130 projecting from the face of the ratchet wheel 106. By the engagement of this pin with the end of the link, the link is moved upwardly to disengage the contact 72 from the cooperating contact 73.

The link 92 is supported so that it may be moved transversely of the plane of the gear 94 to carry the link out of the paths of the pin 129 and the pin 130 and thereby throw the cut-out mechanism out of operation and to carry the link into the path of the pin 129 and thereby throw the cut-out mechanism into operating condition. To this end, the link is loose upon the pivot 90 by which it is connected to the lever 82 so that the link not only can swing about the axis of said pivot but can also swing in a direction transverse to the plane of the gear 94. The coiled spring 126 is arranged with its axis extending in a direction oblique to the plane of the gear 94, as shown in Figs. 9 and 10. This spring tends to move the link longitudinally downwardly, to swing the link to the right about the pivot

90 (Fig. 4) and also tends to swing the link transversely toward the gear wheel 94. A pin 132 mounted on the inner face of the link is arranged to engage the outer face of the gear wheel 94 to limit the movement of the same toward the gear wheel. Return movement of the ratchet wheel after each actuation thereof by the dog 108 is prevented by means of an anti-return dog 134.

The link 92, when held in a position adjacent the gear wheel 94 for more than a predetermined time interval, will be actuated by the pins 129 and 130 in the manner above described to disengage the contact 72 from the contact 73 and thereby break the motor circuit. The link is swung away from the gear wheel 94 to carry the link out of the paths of the pin 129 and the pin 130 by mechanism controlled from the carriage 2.

The means for swinging the link 92 in this manner comprises a lever 140 pivoted at 142 on the plate 76 with which lever engages a laterally extending tongue 144 formed on the link. The lever 140 is provided with an opening 146 into which the tongue 144 projects when the lever is in certain positions. When the lever 140 is in the position shown in Figs. 6 and 8, the tongue 144 engages in the opening 146 in the lever, allowing the link 92 to be positioned by the spring 126 with the link in the path of the pin 129. When the lever is swung from the position shown in these figures to the position shown in Figs. 1 and 4, the portion of the lever at the upper edge of the opening engages the tongue 144 on the link 92 and the link is thereby swung transversely outwardly to carry the same out of the path of the pin 129. The movement of the link 92 is continued by the movement of the lever 140 until the tongue 144 is carried past the lever and the inner end of the tongue rests against the side of the lever as shown in Figs. 1 and 4 when the lever reaches its final position, the lever then holding the link outwardly out of the path of the pin 129.

The lever 140 is swung from the position shown in Figs. 1 and 4 to the position shown in Figs. 6 and 8 by means of the pin 129 which is arranged to engage the lever in the manner shown in Fig. 6, the lever having a curved surface 148 engaged by the pin. Thus the lever is moved into the position shown in Figs. 6 and 8 by the engagement of the pin therewith once during every revolution of the gear 94. When the lever is free to move, upon the disengagement of the pin therefrom, it is moved back into the position shown in Figs. 1 and 4 by a coiled spring 150, its movement being limited by a pin 151.

The movement of the lever back into the latter position is controlled from the type carriage 2. To this end, one arm of the lever is connected by a link 152 with a lever 154 pivoted at 156 upon a projection on the plate 76. This lever extends to a position underneath the gear 20 through which the type carriage is actuated and a stop dog 158 is loosely pivoted at 160 upon the end of this lever. The stop dog is provided with a blunt ended stop arm 162 arranged to engage beneath the gear 20 when the lever 154 is depressed and the stop dog is in vertical position as shown in Fig. 7. The stop dog is provided with a weighted portion 164 which swings the stop dog into vertical position when it is free to assume this position. When the stop dog is engaged by the gear 20 and the gear is rotated in one direction or the other, the stop dog is swung into an inclined position by the action of the gear as shown in Fig. 5.

The swinging of the lever 140 from the position

shown in Figs. 1 and 4 to the position shown in Figs. 6 and 8 depresses the lever 154 and the stop dog 158 is thereby located in a position beneath the gear 20. This movement of the lever 140 also allows the link 92 to be swung transversely by the action of the spring 126 into the path of the pin 129. If the carriage remains at rest, following the movement of the lever 140, for more than a predetermined interval, the pin 129 will engage the link 92, and the link will be moved into the path of the pin 130 and will be actuated by said pin to disengage the contact 72 from the contact 73. If, before the expiration of this time interval, the carriage is shifted, the stop dog 158 will be swung into one of the inclined positions shown in Fig. 5 thereby releasing the lever 154 and the link 152 and the lever 140 will be swung into the position shown in Fig. 4 by the action of spring 126. This movement of the lever will swing the link 92 outwardly out of the path of the pin 129 and the contacts 70 and 72 will be maintained in engagement.

The length of time that the motor will run, after the last operation of the machine or the last movement of the carriage, depends upon the position of the pin 129 with relation to the lever 140 at the end of the last cycle. When operations are following one another in the usual quick succession, the lever 140 holds the link 92 out of the path of the pin 129 during the major part of each revolution of the gear 94. If, during the cycle of operations of the motor cut-out mechanism, the pin 129 moves the lever 140 into the position shown in Fig. 6 and, while it is engaged with the lever and holds said lever from movement sufficient to carry the lever 92 out of the path of said pin, any movement of the carriage is initiated and completed, the lever 140 will be maintained in the position shown in Fig. 6 after the pin disengages the lever and the link 92 will not be moved out of the path of the pin 129 and the pin will move the link into the path of the pin 130 during the same revolution of the gear 94. In this case the contacts 72 and 73 will be disengaged at the end of about three-quarters of a revolution of the gear 94 after the pin leaves the lever 140. This is the minimum time interval that the contacts will remain in engagement after a movement of the carriage. If a movement of the carriage occurs and the lever 140 is swung into the position shown in Figs. 1 and 4 just after the pin 129 passes out of the range of the lever, the gear 94 will then execute about one and one-half revolutions before the contacts 72 and 73 are disengaged. This is the maximum time interval that the contacts will remain in engagement after a movement of the carriage.

When the link 92 has been actuated by the pin 130 to disengage the contact 72 from the contact 73, the mechanism is stopped with the parts substantially in the positions shown in Figure 8. With the mechanism in this condition, in order to start the motor, the carriage is moved either by hand or automatically to release the lever 140 and allow the same to be swung by the action of the spring 126 substantially into the position shown in Figs. 1 and 4. This movement of the lever 140 swings the link 92 outwardly away from the gear wheel 94 to disengage the link from the pins 129 and 130 and the link is then swung to the right and downwardly by the spring 126 into substantially the position shown in Fig. 4. The downward movement of the link releases the spring strip 74 and allows the same to engage

the contact 72 with the contact 73 to close again the motor circuit.

It is to be understood that the terms "time interval," "predetermined interval" and similar terms, employed in the specification and claims of this case, are relative terms related to the speed of the machine. For example, the maximum and minimum time intervals which the motor will run with the carriage idle, will depend upon the speed of the motor, but each will always be substantially the same for the same speed of the motor.

Having explained the nature and objects of the invention and having specifically described a construction embodying the invention in its preferred form, what is claimed is:

1. A record making machine, having in combination, a carriage, an electric motor, a circuit for the motor, automatic means for opening the motor circuit when the motor has been running a predetermined time interval with the carriage idle and mechanism controlled from the carriage for preventing the opening of the circuit by said means when the carriage is moved at intervals less than said predetermined interval.

2. A record making machine, having in combination, a carriage movable in opposite directions transversely of the machine, an electric motor, a circuit for the motor, mechanism for opening the motor circuit when the motor has been running a predetermined time interval without movement of the carriage and means controlled by the movement of the carriage in either direction for preventing the opening of the circuit by said mechanism when the carriage is moved at intervals less than said predetermined interval.

3. A record making machine, having in combination, a carriage, a motor, a switch for controlling the motor, mechanism for opening the switch when the machine is idle for more than a predetermined interval comprising a rotary member connected with the carriage and arranged to be rotated whenever the carriage is moved and means controlled by the rotary movement of said member for preventing the opening of the switch when the carriage is moved at intervals less than said predetermined interval.

4. A machine of the class described, having in combination, a motor, a circuit for the motor, mechanism for breaking the motor circuit when the machine is idle for a predetermined interval comprising a rotary member rotated during each operation of the machine, a tilting stop for engaging said rotary member, a support for said stop, means for moving the support to carry the stop away from the rotary member at regular intervals during the operation of the motor and means for then locating the stop in a position to stop the return movement of said support by its engagement with the rotary member when said member is stationary and thereby condition said mechanism for the breaking of the motor circuit, the engagement of said stop with the rotary member tilting the stop into non-stop position when the said member is rotated.

5. A record making machine, having in combination, a carriage, a motor, a circuit for the motor, a switch for controlling the motor circuit, a member connected for movement with the carriage, means for opening the switch when said member is stationary for at least a predetermined time interval and mechanism controlled by said member for preventing the operation of said switch opening mechanism when said member is

11. A machine of the class described having, in combination, an electric motor, a circuit for the motor, a device movable in one plane into and out of the path of an actuator and in another plane to open the motor circuit, an actuator for moving said device to open said circuit and means controlled by the motor and operating continuously during the operation of the motor for moving the actuator progressively in timed relation to the operation of the motor. 10
12. A machine of the class described having, in combination, an electric motor, a circuit for the motor, a timing device operated by the motor, a circuit breaking device movable in one plane into and out of the path of the timing device and in another plane into and out of the path of an actuator, an actuator operated by the motor for moving said device to break the motor circuit and mechanism operating continuously during the operation of the motor for 20 moving the actuator. 15
13. A machine of the class described having, in combination, an electric driving motor, a switch having contacts in the motor circuit for controlling the motor, a timing device controlled by the motor for timing the interval of operation of the motor before the actuation of the switch to break the motor circuit and a switch operating device operated by the motor and movable in one plane into and out of the path of the timing device and in another plane to disengage the switch contacts. 25
14. A machine of the class described having, in combination, an electric driving motor, a switch having contacts in the motor circuit for controlling the motor, a timing device controlled by the motor for timing the actuation of the switch to disconnect the motor circuit, a member movable in one plane to disengage the switch contacts and in another plane into and out of 30 the path of the timing device, a movable controlling device for controlling the position of said member in the second plane, means for moving said device into position to allow said member to move into the path of the timing device and 35 means for preventing the return of said controlling device when the machine thereafter is idle. 40
15. A record making machine, having in combination, a carriage, an electric motor, a circuit for the motor, mechanism for breaking the motor circuit when the machine is idle for a predetermined interval, means for resetting said mechanism and mechanism for controlling the action of said means comprising a pivotally movable member acting as a stop when in one angular position to prevent said means from resetting said mechanism and swung into non-stop position by movement of the carriage to permit said means to reset said mechanism. 45
16. A record making machine, having in combination, an electric motor, a circuit for the motor, a switch for controlling the circuit, mechanism for opening the switch when the machine is idle for a predetermined time interval, means for resetting said mechanism and mechanism for controlling the action of said means comprising a pivotally movable member acting as a stop when in one angular position to prevent said means from resetting said mechanism and swung into non-stop position when certain parts of the machine are actuated to permit said means to reset said mechanism. 50
17. A record making machine, having in combination, a motor, a switch for controlling the motor, means for controlling the switch comprising a link bodily movable to open the switch and pivotally movable in two different planes, a timing device controlled by the motor for moving the link in one plane into the path of an actuating device, an actuating device for moving the link bodily, operated by the motor in timed relation to the timing device and means for moving the link in another plane out of the path of the timing device. 55
18. A record making machine, having in combination, a carriage, an electric motor, a circuit for the motor, automatically operating mechanism for opening the motor circuit when the motor has been running a predetermined time interval with the carriage idle and means set by the movement of the carriage to prevent the opening of the motor circuit by said mechanism when the carriage is moved at intervals less than said predetermined interval. 60

OSCAR J. SUNDSTRAND.
